Application May 4, 1953, Serial No. 352,918

3 Claims. (Cl. 62—2)

This invention relates generally to refrigerator defrost systems, and more specifically to an improved refrigerator defrost termination control system wherein a gas-filled capillary tube and a bellows comprises a portion of the control system.

The use of a gas-filled capillary tube and a bellows in a refrigerator defrost termination control system to detect a certain temperature rise of the refrigerator evaporator to indicate the completion of the defrosting of the evaporator, and to actuate the bellows to terminate the defrost cycle, gives rise to a number of problems. In a system of this nature it has been found that the coldest point on the capillary tube and the bellows is the controlling point. This results from the fact that the pressure exerted by the bellows will be a direct function of the temperature of the gas within the capillary tube and the bellows at the coldest point thereof. This is a disadvantage in that refrigerator evaporators are usually heated by electrical heating coils, and often, during the defrosting cycle, especially when the interior of the refrigerator cabinet has been maintained at a comparatively low temperature, the evaporator surface may become considerably warmer than the cabinet interior. Thus, the closed end of the capillary tube, which is in contact with the evaporator surface, will be at a temperature substantially above other portions of the capillary tube and the bellows. In this case some other point along the capillary tube or the bellows will be the controlling point for the termination of the defrost cycle. The defrost cycle will continue until all points along the capillary tube and the bellows are above the cut-off temperature. By this time the temperature of the evaporator may be such that any frozen foods which may be positioned within the evaporator will be melted. If an attempt is made to overcome this disadvantage by a lowering of the cut-off temperature of the termination control system, the defrost cycle will be terminated in a shorter period of time, when the refrigerator cabinet is operated at a comparatively high temperature, with the result that the evaporator will not be completely defrosted, since at higher cabinet temperatures the same or even longer periods of defrosting may be required to melt all of the ice formed on the evaporator.

Therefore, it is an important object of this invention to provide a refrigerator defrost termination control system comprising a capillary tube and a bellows wherein the end of the capillary tube will at all times remain the controlling point.

It is a further object of this invention to provide a refrigerator defrost termination control system which will efficiently permit the use of a low cut-off temperature for the termination of the defrost cycle.

It is a further object of this invention to provide a refrigerator defrost termination control system which will permit effective defrosting at comparatively high or low cabinet temperatures.

It is a feature of this invention that a novel water

container is mounted in cooperation with an evaporator surface, a capillary tube and a bellows.

It is a further feature of this invention that defrost water is used to constantly maintain the novel water container filled.

Other objects and features of the present invention will be apparent upon a perusal of the following specification and drawing of which

Figure 1 is a partial cross-sectional side view of a refrigerator cabinet embodying the present invention; and,

Figure 2 is a front plan view of the refrigerator cabinet shown in Figure 1 with the refrigerator door removed.

The present embodiment is the preferred embodiment but it is to be understood that changes can be made in the present embodiment by one skilled in the art without departing from the spirit and scope of this invention.

For a detailed description of the invention reference is made to the drawing wherein a refrigerator cabinet 5 is shown with a refrigerator door 6 mounted over the open side thereof to define a food compartment 7. The refrigerator cabinet 5 and the refrigerator door 6 may be of any type well known in the art. A rectangularly shaped refrigerator evaporator 8 is mounted within the upper portion of the food compartment 7 by means of the mounting means 9. The refrigerator evaporator 8 and the mounting means 9 may be of any type well known in the art. The evaporator 8, as shown, comprises a length of serpentine tubing 10 mounted to the evaporator in thermal contact therewith. As is well known in the art, the evaporator tubing 10 serves to conduct refrigerant therethrough to cool the evaporator surfaces and to cool the food compartment 7. The ends of the serpentine tube 10 are connected into the remainder of a conventional refrigerator system (not shown). Such a conventional refrigerator system includes control means for causing the food compartment 7 to be maintained at different ranges of temperatures. The space 11 disposed within the evaporator 8 comprises the conventional refrigerator freezer compartment. Frozen food may be placed within the compartment 11, upon the surface 12, and upon the rack 13, and further in thermal contact with the two side walls 14. Frozen foods so placed will be maintained at freezing temperatures by the evaporator 8.

As is well known in the art, frost will form upon the surfaces of the evaporator after a certain period of operation thereof. To remove this accumulation of frost it is necessary to periodically defrost the evaporator, and to accomplish this purpose a conventional heating coil 15 is provided, and is mounted in thermal contact with the outer surfaces of the evaporator 8. The ends 16 of the heating coil 15 are connected to any conventional power supply and defrost cycle initiating means (not shown). Thus when the defrost cycle is initiated, current will flow through the heating coil 15 to heat the coil 15.

The heat from the heating coil 15 will in turn be conducted to the surfaces of the evaporator 8 to melt the frost accumulations therefrom. Should the heating coil 15 be energized for a period longer than necessary to melt the frost, any frozen foods within compartment 11 may be melted. Within a portion of the heating coil 15, a switch 17 is connected. The switch 17 comprises a stationary contact 18 and a movable contact arm 19. The contact 18 and the contact arm 19 are biased to a normally closed position by the spring 20. Thus, it can be seen that when the movable contact arm 19 is moved from contact with the contact 18, the heating circuit 15 for the defrosting of the evaporator is opened.

70

To open and close the switch 17, a bellows element 21 is provided. The bellows 21 is so formed as to expand and contract with changes of the internal pressure therein. To provide means for changing the pressure within the bellows 21 a length of tubing 22 is provided. One end of the length of tubing 22 is connected into one side of the bellows 21. The other end of the length of tubing 22 is sealed, and the length of tubing 22 and the bellows 21 are filled with a gas, so that when the length of tubing 22 is cooled, the gas disposed therein will cool to cause the pressure therein to decrease, to cause the bellows 21 to contract. Further, if the length of tubing 22 is heated, the gas disposed therein will expand, to in turn cause the bellows 21 to expand. The other side of the bellows 21 is pivotally connected to the movable contact arm 19 as can easily be seen in Figure 1, so that any expansions and contractions of the bellows 21 will cause a movement of the contact arm 19 against and aided by the bias of the spring 20, respectively. The pivotal connection of the bellows to the arm 19 is made adjustable by any means well known in the art so that the cut off temperature of the termination control may be varied. The length of tubing 22 is fixedly maintained adjacent to one side of the evaporator 8 by means of the mounting means 23. The closed end of the length of tubing 22 is disposed within a container 24.

The container 24 is generally shaped as a four sided trough, and the top thereof is open. The container 24 is mounted in thermal contact with one side of the evaporator 8 by means of the mounting means 25. The container 24 is filled with water or ice dependent upon the temperature of the evaporator. Since the container 24 is mounted against one side of the evaporator and since the top of the container 24 is open, the container 24 will be maintained full of water by defrost water running from the outer surfaces of the evaporator 8 during the defrost cycle. Therefore, during the refrigeration cycle the water disposed within the container 24 will be frozen with the result that the closed end of the length of tubing 22 will be encased within a block of ice.

To describe the operation of the instant invention it will be first assumed that the food compartment 7 is being maintained at a comparatively low temperature. The termination control may be adjusted to a low cut-off temperature. The closed end of the capillary tube 22 which is encased in the block of ice will be at the lowest temperature, and the closed end of the capillary tube 22 will remain at the lowest temperature until the block of ice is completely melted. The time required to melt the block of ice will be ample for proper defrosting and the low cut-off temperature will prevent the evaporator from becoming excessively warm. Thus, after the ice in the container 24 has melted, the water may be heated to some temperature such as 40°, at which time the gas within the capillary tube 22 and the bellows 21 will expand sufficiently to move the contact arm 19 from contact with the contact 18 to stop the defrost cycle.

When the cabinet temperature is maintained at a comparatively high temperature, the bellows and a large portion of the capillary tube 22 will be at a substantially higher temperature than the closed end of the capillary tube 22. The block of ice about the closed end of the capillary tube 22 will prevent the end of the closed end of the tube 22 from increasing above the temperature at which the ice will melt until all of the ice within the container 24 has melted. This delay action will provide ample time for proper defrosting of the evaporator at the comparatively high cabinet temperatures.

Having described the invention in detail what is considered new and desired to be protected by Letters Patent is:

1. In a refrigeration system having an evaporator and a means for defrosting said evaporator, a defrost termination control comprising a container mounted to one wall of said evaporator in thermal contact therewith, a

quantity of ice disposed within said container when said evaporator is operating on a refrigeration cycle, said container formed in the shape of an open trough so that any water frozen therein can expand without breaking said container and so that any water and ice lost therefrom by evaporation is replaced by defrost water flowing over the surfaces of said evaporator and into said trough-shaped container, a length of tubing being closed at one end thereof, a bellows, the other end of said length of tubing being connected to one end of said bellows, a certain amount of a gas disposed within said length of tubing and said bellows, said gas of an amount sufficient to cause the operation of said bellows on an expansion thereof responsive to a rise in temperature of the entire length of said length of tubing some temperature above the freezing temperature of water, said closed end of said length of tubing being disposed within said container whereby said closed end of said length of tubing is maintained at a temperature below the freezing temperature of water when said means for defrosting said evaporator is operating until said ice disposed within said container is melted, and means connected to the other end of said bellows and operating responsive to the operation of said bellows for terminating said means for defrosting said evaporator.

2. In a refrigeration cabinet having an evaporator disposed therein which is selectively operable to one position to maintain said cabinet at a low temperature and selectively operable to another position to maintain said cabinet at a high temperature and having means for defrosting said evaporator, a defrost termination control comprising a length of tubing being closed at one end, a bellows, the other end of said length of tubing being connected to one end of said bellows, said length of tubing and said bellows being positioned within said cabinet, a certain amount of gas disposed within said length of tubing and said bellows, said gas of an amount sufficient on the expansion thereof to cause the operation of said bellows responsive to a heating of said length of tubing and said bellows along the entire length thereof above a certain predetermined temperature above the freezing temperature of water, and means for preventing the closed end of said length of tubing from rising above said certain predetermined temperature for a predetermined length of time when said cabinet is maintained at said low temperature and for maintaining said closed end of said length of tubing below said certain predetermined temperature for a predetermined length of time when said refrigerator cabinet is maintained at said high temperature, said last mentioned means comprising a container, said container mounted in thermal contact with one surface of said evaporator, a quantity of ice disposed within said container, said container formed in the shape of an open trough so that any water and ice lost therefrom by evaporation is replaced by defrost water flowing over the surfaces of said evaporator and into said trough-shaped container, and said container being so positioned that said closed end of said length of tubing is positioned within said container, and means operating responsive to the operation of said bellows for terminating said means for defrosting said evaporator.

3. In a refrigeration cabinet, an evaporator disposed within said cabinet, means selectively operable to one position for causing said evaporator to maintain said cabinet at a low temperature and selectively operable to another position for causing said evaporator to maintain said cabinet at a high temperature, means operable to defrost said evaporator, a defrost termination control comprising a length of tubing being closed at one end, a bellows, said length of tubing and said bellows being positioned within said cabinet, the other end of said length of tubing being connected to one end of said bellows, a certain amount of gas disposed within said length of tubing and said bellows, said gas of an amount sufficient on the expansion thereof to cause the operation of said

bellows responsive to a heating of said length of tubing and said bellows along the entire length thereof above a certain predetermined temperature above the freezing temperature of water, and means for preventing the closed end of said length of tubing from rising above said certain predetermined temperature for a predetermined length of time when said cabinet is maintained at said low temperature and for maintaining said closed end of said length of tubing below said certain predetermined temperature for a predetermined length of time 10 when said refrigerator cabinet is maintained at said high temperature, said last mentioned means comprising a container, said container mounted in thermal contact with one surface of said evaporator, a quantity of ice disposed within said container, said container formed in 15 the shape of an open trough so that any water and ice

lost therefrom by evaporation is replaced by defrost water flowing over the surfaces of said evaporator and into said trough-shaped container, said container being so positioned that said closed end of said length of tubing is positioned within said container, and means operating responsive to the operation of said bellows for terminating said means for defrosting said evaporator.
